PHOTOGRAPHIC PRINTING APPARATUS

Joel W. Bravo, Binghamton, N.Y., assignor to General Aniline & Film Corporation, New York, N.Y., a corporation of Delaware

Filed Jan. 17, 1962, Ser. No. 68,347

Term of patent 14 years

(Cl. D61—1)

FIG. 2

FIG. 1

FIG. 1 is a front elevational view of a photographic printing apparatus showing my new design;

FIG. 2 is a front perspective view thereof.

The side not shown is substantially identical with the side shown, and the rear thereof is plain and unornamented.

I claim:

The ornamental design for a photographic printing apparatus, substantially as shown and described.
